(57) CLAIM

The ornamental design for a mascara bottle, as shown and described.

DESCRIPTION

FIG. 1 is a perspective view of a mascara bottle showing my new design;

FIG. 2 is a top view thereof;

FIG. 3 is a bottom view thereof;

FIG. 4 is a right side view thereof, the left side view being a mirror image thereof; and,

FIG. 5 is a front view thereof, the rear view being a mirror image thereof.

The broken lines in the drawings illustrate the portions of the mascara bottle that form no part of the claimed design.
